SCRAPER

Donald L. Hartkopf, Huntington Park, Calif.

Application August 7, 1958, Serial No. 753,668

1 Claim. (Cl. 15—236)

This invention relates to new and useful improvements in scraping implements for use particularly in bakeries, pastry shops, etc., and has for its primary object to provide, in a manner as hereinafter set forth, a device of this character wherein the blade may readily be removed when desired for replacement or cleaning.

Another important object of the present invention is to provide, in a scraper of the aforementioned character comprising a separable holder and blade, novel means for firmly but removably mounting said blade on said holder without the use of bolts, screws or other extraneous securing elements.

Other objects of the invention are to provide a scraper of the character described which will be comparatively simple in construction, strong, durable, compact, of light weight, sanitary and which may be manufactured at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in front elevation of a scraper constructed in accordance with the present invention;

Figure 2 is an enlarged view in vertical section, taken substantially on the line 2—2 of Figure 1; and

Figure 3 is a perspective view of the device, showing the holder and blade separated.

Referring now to the drawing in detail, it will be seen that the embodiment of the invention which has been illustrated comprises a holder which is designated generally by reference character 4. The holder 4 is formed from a single sheet or plate 5 of stainless steel or other suitable resilient material and comprises a substantially rectangular handle 6. Formed integrally with the lower edge 7 of the plate 5, as at 8, is a pair of spaced, tapered, resilient clips 9 which open downwardly. The clips 9 are in back of the plate 5 adjacent the ends thereof.

Removably mounted on the holder 4 is an elongated blade of plastic or other suitable resilient material which is designated generally by reference character 10. The blade 10 is slidably insertable endwise in the clips 9 where it is frictionally retained. The blade 10 includes

2

an upper or back portion 11 of substantially tapered or ovate transverse section for engagement in the clips 9. The blade 10 is further provided, on its front and adjacent the bottom or base of the back 11, with a shoulder 14 or lip the top of which is grooved to provide a seat 15 for the lower edge 7 of the plate 5. This is shown to advantage in Figure 2 of the drawing.

It is thought that the use of the device will be readily apparent from a consideration of the foregoing. Briefly, the resilient clips 9 are tensioned when the back 11 of the blade 10 is forced thereinto from either end of the plate 5, thus frictionally securing said blade in position. The grooved lip or shoulder 14 shields the lower edge 7 of the plate 5 and stabilizes the blade 10 on the holder 4 in an obvious manner. The handle 6 of the holder 4 may be readily gripped in either hand when using the tool. Added pressure may be applied to the scraping edge 13 of the blade 10 by engaging the fingers of the hand which grips the handle 6 with the back 11 of said blade. The back 11 of the blade 10 also shields the fingers of the hand from the work. Of course, when the blade 10 becomes worn or damaged it may quickly be removed for replacement. The removability of the blade 10 also facilitates cleaning and maintaining the implement in a highly sanitary condition at all times. The device is particularly useful for scraping kettles in bakeries.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

A scraping implement of the character described comprising: a holder including a resilient plate comprising a straight edge portion, spaced resilient clips on one side of the plate integral with said straight edge portion thereof, and an elongated, resilient blade removably mounted on the holder and including a longitudinal scraping edge, said blade further including an integral, longitudinal back member of tapered transverse section slidable endwise into the clips for tensioning the same and frictionally securing said blade on said plate, said blade still further including a longitudinal shoulder paralleling said back member and having a longitudinal groove therein providing a seat for the reception of the plate.
